DOOR OPENING AND DOOR CHECKING
DEVICEEdwin L. Allen, Cleveland Heights, Ohio, assignor
to Rudolph I. Schonitzer, Shaker Heights, Ohio

Application February 5, 1940, Serial No. 317,293

15 Claims. (Cl. 16—86)

This invention relates to door opening devices and to combining door opening and door checking devices, said devices preferably being of such character that they yieldingly resist (but only to a desirable degree) the closing of the doors with which they are used from the open positions to which said doors are automatically movable by said devices. As will hereinafter appear, devices embodying the present invention are particularly 10 adapted for use with doors which are so hinged on their supporting structures that the hinge edge walls of said doors and the hinge edge walls of said supporting structures are in oppositely positioned or generally abutting relationship when 15 said doors are in their closed positions, such as the doors of automobiles or the like, for example.

One of the objects of the present invention is the provision of a door opening device which automatically effects, upon the unlatching of the door with which it is used, the movement of said door to any desired open position, either a partially open position or the fully open position of said door.

Another object of the present invention is the provision of a device which not only is effective, upon the unlatching of the door with which it is used, to automatically move said door to any desired open position but which also is effective to yieldingly resist (but only to a desirable degree) the closing of said door from the position to which it is automatically movable. Therefore, if the open position to which said door is automatically movable is the fully open position of said door, said door will be releasably held or retained in its fully open position, and as a result, the use of separate holding means for that purpose is wholly unnecessary. If, on the other hand, the open position to which said door is automatically movable is a partially open position thereof, the closing of said door from said partially open position will be yieldingly resisted by such device, and if said door has a normal tendency to close, like most present-day automobile doors, said door will remain in such partially open position unless it is manually closed or manually moved to a further open position.

Another object of the present invention is the provision of a combined door opening and door checking device which is effective, upon the unlatching of the door with which it is used, to automatically open said door to any desired extent, and to check or arrest the opening movement of said door when it reaches its fully open position, thereby making wholly unnecessary the

use of separate means for such door checking purpose.

Another object of the present invention is the provision of a device which is effective, upon the unlatching of the door with which it is used, to automatically open said door to any desired extent, to check the opening movement of said door when it reaches its fully open position, and to yieldingly resist (but only to a desirable degree) the closing of said door from the open position to which it is automatically movable.

Another object of the present invention is the provision of a door opening device which can be readily converted into a combined door opening and door checking device by the mere mounting 15 of bumper means on the arm thereof, and conversely, the provision of a combined door opening and door checking device from which the checking function thereof can be readily eliminated by the mere removal of the bumper means 20 from the arm thereof.

Other features of devices embodying the present invention are their structural simplicity, which enables them to be made and sold at low cost; their strong and rugged character, which 25 enables them to have an exceedingly long life in service without requiring attention from time to time; and the efficiency with which they perform their intended functions, namely, the function of automatically opening to any desired extent 30 the doors with which such devices are used and the function of yieldingly resisting (but only to a desirable degree) the closing of said doors from the positions to which they are automatically opened; or those two functions with the additional function of checking or arresting the opening movement of said doors when they have reached their fully open positions.

Further features of devices embodying the present invention are in part obvious and in part will appear from the following description of three such devices, reference being had to the accompanying drawings, in which

Fig. 1 is an outside elevation of a portion of a left front automobile door and that portion of the automobile body on which said door is hinged, parts of the outer side walls of said door and body portions being broken away to expose the combined door opening and door checking device associated therewith, said door being in its closed 45 position; Fig. 2 is a horizontal sectional view, on an enlarged scale, through said door and body portions, the view being on the line 2—2, Figs. 1 and 3; Fig. 3 is a vertical sectional view through said door and body portions, the view being on 50 55

the line 3—3, Fig. 2; Fig. 4 is a view corresponding to Fig. 2 but showing the door in its fully open position (the position to which it is automatically movable); Fig. 5 is a view corresponding to Fig. 2 and showing a device which differs from the device of Figs. 1 to 4 inclusive only in that it has no door checking function; Fig. 6 is a vertical sectional view through a portion of a left front automobile door and a part of that portion of the automobile body on which said door is hinged and showing associated therewith a combined door opening and door checking device having its arm pivotally secured to said body portion rather than to said door, the view being on the line 6—6, Fig. 7; and Fig. 7 is a horizontal sectional view through the door and body portions of Fig. 6, the view being on the line 7—7, Fig. 6, and showing in dotted lines the fully open position of said door (the position to which said door is automatically movable).

Before the present invention is described in detail, it is to be understood that such invention is not limited to the details of construction or the specific arrangement of parts herein illustrated or described, as the invention obviously may take other forms. It also is to be understood that the phraseology or terminology herein employed is for the purpose of description and not of limitation.

Although devices embodying the present invention are applicable for use with any hinged door having its hinge edge wall oppositely positioned or in generally abutting relationship with respect to the hinge edge wall of its supporting structure (the structure on which said door is hinged), said devices are particularly useful with the doors of automobiles or the like, and for purposes of illustration and not of limitation, the use of three of such devices with present-day automobile doors is here shown and described.

Referring first to Figs. 1 to 4 inclusive, the reference numeral 1 designates a portion of a left front automobile door, said door having its transverse front edge wall 2 suitably hinged, as is usual, on the transverse rear edge wall 3 of that portion of the automobile body shown in Figs. 1 to 4 inclusive and designated generally by the reference numeral 4, a pair of concealed hinges 5 being used for that purpose, the hinge axis 6 of said door being indicated in Figs. 1 to 4 inclusive. As best shown in Fig. 2, when the door 1 is in its closed position, the door and body edge walls 2 and 3 (which edge walls are hereinafter termed "hinge edge walls") are in oppositely positioned or generally abutting relationship, by which is meant that such hinge edge walls are oppositely positioned or disposed and either in actual contact or, as here shown, relatively close to each other.

Although any suitable means may be utilized for releasably retaining the door 1 in its closed position (the position of said door in Figs. 1 to 3 inclusive) and for actuating said retaining means to release said door for opening movement (said retaining means being hereinafter referred to broadly as "latch means"), devices embodying the present invention are particularly useful in conjunction with doors whose latch means have push-buttons or the like for effecting release actuation of said latch means, as the opening of said doors, to any extent desired, is automatically effected by the present devices. Projecting door handles, by the use of which present-day automobile doors are unlatched and manually opened, not only are dangerous (in that many severe

injuries have been caused by them) but also, said projecting handles seriously interfere with the streamlining effects now desired for automobile bodies. Inasmuch as the devices here involved automatically effect, upon the unlatching of the doors with which they are used, the movement of said doors to the open positions desired therefor, the use with said doors of the present-day handles for door opening purposes is wholly unnecessary. As a result, simple push-buttons or the like, desirable from many standpoints, may be used with the latch means of doors with which are used the devices here involved.

The latch means, therefore, of the automobile door 1 of Figs. 1 to 4 inclusive may be, and preferably is, of the type in which push-buttons or the like are utilized for effecting release actuation thereof. For example, said latch means may be of the form disclosed in the Schonitzer Patent No. 2,094,413 for Door control mechanism, to which patent reference may be had, if desired. However, inasmuch as the latch means of the door 1 forms no part of the present invention, no latch means for such door is here shown or described.

As will hereinafter more fully appear, each of the devices here illustrated (devices which are capable of automatically swinging relatively heavy doors, such as present-day automobile doors to partially open positions thereof or to their fully open positions) is of simple and inexpensive character and of such compact form that it may be easily and conveniently mounted between the general planes of the inner and outer side walls of an automobile door and the general planes of the inner and outer side walls of that portion of the automobile body on which said door is hinged, there being (see Figs. 2, 5 and 7) more or less alignment of the outer side wall of such a door and the outer side wall of such a body portion and more or less alignment of the inner side wall of such a door and the inner side wall of such a body portion, when said door is in its closed position.

As a result, the devices here involved not only are eminently satisfactory from structural and functional standpoints but also, are commercially practical for present-day automobile doors, as such devices are concealed from view when the doors with which they are used are in their closed positions, and their exposure, even when such doors are in their fully open positions, is such that they are entirely unobjectionable.

Although the devices here involved may take various forms, the combined door opening and door checking device illustrated in Figs. 1 to 4 inclusive includes an arm 8, the rear end of which is pivotally connected, in any suitable manner and by any suitable means, to the automobile door 1, between the general planes of its inner and outer side walls 7 and 8, the general plane of each such side wall, as that term is here used, being the plane which not only includes such side wall but which also extends theretond. The free or forward end portion of said arm lies within the automobile body portion 4 and hence is located between the general planes of its inner and outer side walls 9 and 10, there being, for the extension therethrough of said arm, a suitable aperture 11 in the hinge edge wall 3 of said body portion and a suitable aperture 12 in the transverse wall 13 of the sheet metal reinforcement pillar 14 with which such body portion is here provided. As here shown,

the arm 6 is in the form of a plain metal rod of generally cylindrical form, the rear end of said arm being suitably flattened for pivotal connection, by the use of a rivet 16 or the like, to the forward end of a longitudinally bent or arcuately shaped sheet metal bracket 17, the diverging base flanges 18 of which bracket are screwed or otherwise suitably secured to the door hinge edge wall 2.

Arranged within the automobile body portion 4 is a generally U-shaped sheet metal bracket 20 having upper and lower side walls 21 and 22 and a front end wall 23 by which said side walls are connected at their forward ends, the side walls of said bracket being generally horizontal and the front end wall of said bracket being generally vertical, as here shown. For the securement of said bracket to the automobile body portion 4, the bracket side walls 21 and 22 are here provided at their rear ends with diverging flanges 24, which are bolted or otherwise suitably secured to the transverse pillar wall 13, and said bracket side walls are also here provided at their inner sides with diverging flanges 25, which are screwed or otherwise suitably secured to the inner side wall 9 of said automobile body portion. As best shown in Figs. 1 and 3, the arm 6, which is generally horizontally disposed, lies between the upper and lower bracket side walls 21 and 22 and extends through a suitable aperture 27 in the generally vertical bracket front end wall 23, and although such bracket wall may be used, if desired, for guiding said arm, in its reciprocatory movement as the door 1 is opened and closed.

35 a suitably apertured rubber pad 28 or the like is here utilized for such arm guiding purposes, said pad being riveted or otherwise suitably secured to the bracket wall 23 and lying alongside the front surface thereof.

40 For automatically effecting the desired opening movement of the door 1, upon the unlatching thereof, the device of Figs. 1 to 4 inclusive is provided with expansible means in the form of a coiled compression spring 30, which surrounds the arm 6 and abuts at its forward end the body bracket wall 23. Although the rear end of said spring may abut any suitable part of the door 1, the rear end of said spring here engages or bears against suitable abutment means with which said 45 arm 6 is provided. As here shown, the arm is provided, adjacent its pivotal axis, with a suitable aperture for the reception of a cotter pin 31 or the like, and although the rear end of the compression spring 30 may directly engage said cotter pin, if desired, a sheet metal washer 32 is here interposed between said spring and said cotter pin.

50 The compression spring 30 is therefore confined between two abutment means, namely, one carried by the automobile body portion 4 (the bracket front end wall 23) and the other carried by the arm 6 (the cotter pin 31 and the washer 32), and inasmuch as said arm is pivotally connected to and moves with the door 1, said spring 55 is effective, through the force of its expansion, to automatically open said door, upon the unlatching thereof. As will be readily understood, the location of said arm abutment means relative to said body abutment means is such that during the movement of the door 1 to its closed position, the spring 30 confined between said two abutment means is compressed, and thereby loaded, to the desired degree, and upon the unlatching of said door, said spring automatically 60 effects the movement of said door to the desired

open position. Although such position of said door may be a partially open position thereof, as heretofore pointed out, the position to which said door is automatically movable, as here shown, is its fully open position, a position which 5 is determined by the present device in the performance of its door checking function, as will hereinafter appear. If it is desired that the door 1 be automatically movable to a partially open position only, it is merely necessary to replace 10 the compression spring 30 by a compression spring which is incapable of automatically moving said door beyond such partially open position, as will be readily understood.

As heretofore pointed out, devices embodying 15 the present invention not only automatically effect, upon the unlatching of the doors with which they are used, the opening of said doors to the extent desired but also, yieldingly resist the closing of said doors from the positions to which they 20 are automatically opened. Inasmuch as the compression spring 30 of the device of Figs. 1 to 25 4 inclusive is effective to fully open the door 1, closing movement of said door from its fully open position is yieldingly resisted, and as a result, said door is releasably held or retained in its fully open position whenever it is moved thereto. With the device of Figs. 1 to 4 inclusive, therefore, no separate holding means is necessary for the door with which such device is 30 used. If, on the other hand, the door 1 were automatically movable by said device to a partially open position only, and if the releasable retention of said door in its fully open position were desired, the use of separate or additional 35 holding means for said door would be necessary for that purpose, although the closing of said door from said partially open position would be yieldingly resisted, of course, by such door opening device. If said door had a normal tendency 40 to close, like most present day automobile doors, it would remain, of course, in the partially open position to which it was automatically movable, unless it were manually closed or manually moved to a further open position, all as will be 45 readily understood.

For the accomplishment of its door checking function, the device of Figs. 1 to 4 inclusive is provided, on the free or forward end portion of its arm 6, with suitable bumper means for checking contact, when the automobile door 1 has been opened the desired extent, with suitable abutment means with which the automobile body portion 4 is provided. Although said arm bumper means and the body abutment means engaged 50 thereby may both be of rigid character, the effect of which would be the checking or arresting, in a non-yieldable manner, of the opening movement of the door 1, it is desirable to have either said arm bumper means or said body abutment 55 means, or both, of resilient character, in order that the opening movement of said door may be yieldingly checked or arrested. As here shown, the bumper means of said arm engages, when said door has been opened the desired extent, 60 the arm-guiding rubber pad 28 on the front face of the body bracket wall 23, and it is therefore unnecessary that said arm bumper means be of resilient character in order that the checking or arresting of the opening movement of said door 65 be of yieldable character. As here shown, however, the bumper means of the arm 6 comprises a bumper member in the form of a rubber block 70 34, the retention of which block on said arm is here effected by a cotter pin 35 or the like with 75

which said arm is provided, a metal washer 36 being interposed, if desired and as here shown, between said cotter pin and said rubber bumper block.

5 From the foregoing description of the combined door opening and door checking device of Figs. 1 to 4 inclusive, and from the foregoing explanation of its operation it will be apparent that when the door 1 is in its closed position, the 10 coiled compression spring 30 is sufficiently compressed between its two abutment means to put said spring in the desired loaded condition. Upon the unlatching of said door, said spring effects, through the force of its expansion, the 15 automatic movement of said door to its fully open position, and such door opening movement is yieldingly checked or arrested, when said door reaches its fully open position, by the engagement of the arm bumper member 34 with the arm-guiding pad 29 of the body bracket wall 23. As 20 closing movement of said door is yieldingly resisted, to the extent desired, by the compression resistance of said expanded spring, said door will be releasably held or retained in its fully open 25 position, all as will be readily understood.

It is not necessary, of course, that all devices embodying the present invention be capable of performing the three functions of the device illustrated in Figs. 1 to 4 inclusive and heretofore 30 described, namely, (a) the function of automatically opening, to any extent desired, the door with which it is used; (b) the function of yieldingly resisting closing movement of said door from the position to which it is automatically 35 opened; and (c) the function of checking or arresting the opening movement of said door when it reaches its fully open position. It is to be understood, therefore, that the present invention embraces and includes devices which do not 40 have a door checking function, but merely the function of automatically opening the doors with which they are used and the function of yieldingly resisting the closing of said doors from the 45 positions to which said doors are automatically opened.

In Fig. 5 there is illustrated, therefore, a device which differs from the device of Figs. 1 to 4 inclusive chiefly in that it has no arm bumper means and hence, is incapable of checking or 50 arresting the opening movement of the left front automobile door 1a with which it is used. The device of Fig. 5 has, of course, the other two functions of the device of Figs. 1 to 4 inclusive, and therefore (a) automatically effects the movement of the door 1a to the desired open position, upon the unlatching of said door, and (b) yieldingly resists the closing of said door from the open position to which it is automatically movable. Inasmuch as the parts which the device of Fig. 5 includes or comprises are either identical with or quite similar to the corresponding parts of the device of Figs. 1 to 4 inclusive, the parts of the device of Fig. 5 bear reference designations 55 which differ from the reference numerals of the corresponding parts of the device of Figs. 1 to 4 inclusive only by the suffix letter "a".

Although the arm 6 of the door opening and door checking device of Figs. 1 to 4 inclusive is 70 pivotally connected to the automobile door 1 and extends into the automobile body portion 4, and the arm 6a of the door opening device of Fig. 5 is pivotally connected to the automobile door 1a and extends into the automobile body portion 4a, 75 the arm of either device, if desired, may be

pivotally connected to the automobile body portion and extend into the automobile door.

Such a reversal in the mounting of a combined door opening and door checking device, like that or similar to the device of Figs. 1 to 4 inclusive, is illustrated in Figs. 6 and 7, and inasmuch as the device of Figs. 6 and 7 is quite similar to the device of Figs. 1 to 4 inclusive, the two devices have their corresponding parts indicated by reference designations which differ only by the suffix 10 letter "b".

As to the device of Figs. 6 and 7, it is to be noted that the arm 6b is pivotally connected to a bracket 17b suitably secured to the hinge edge wall 3b of the automobile body portion 4b; that said arm 15 extends into the left front automobile door 1b through a suitable opening 11b in the door hinge edge wall 2b; and that the bracket flanges 24b and 25b are secured, respectively, to the hinge edge wall 2b and the inner side wall 7b of the door 20 1b. For the performance of its three functions (namely, (a) the function of automatically swinging to its fully open position (as here shown) the door 1b upon the unlatching thereof; (b) the function of yieldingly resisting the closing of 25 said door from such fully open position; and (c) the function of yieldingly checking or arresting the opening movement of said door when it reaches its fully open position), the device of 30 Figs. 6 and 7 operates in the same manner as the device of Figs. 1 to 4 inclusive and as a result, no further reference to the device of Figs. 6 and 7 is believed to be necessary.

Further features and advantages of devices embodying the present invention will be readily 35 apparent to those skilled in the art to which such invention relates.

What I claim is:

1. A device for automatically moving to an open position a closed but unlatched door structure hinged on a supporting structure, said device comprising an arm pivotally secured to one of said structures and extending into the other structure, abutment means associated with and located within the structure into which said arm extends, a second abutment means opposed to the first named abutment means, and a compression spring means surrounding said arm and confined between said two abutment means, the confinement of said spring means between said two abutment means effecting the desired loading of said spring means during the closing of the door structure and said spring means when so loaded being effective to automatically move said door structure, if closed and unlatched, to an open position.

2. A device for automatically moving to an open position a closed but unlatched door structure hinged on a supporting structure, said device comprising an arm pivotally secured to one of said structures and extending into the other structure, abutment means associated with and located within the structure into which said arm extends and constituting a guide for said arm, a second abutment means opposed to the first named abutment means, and expandible means carried by said arm and confined between said two abutment means, the confinement of said expandible means between said two abutment means effecting the desired loading of said expandible means during the closing of the door structure and said expandible means when so loaded being effective to automatically move said door structure, if closed and unlatched, to an open position.

3. A device for automatically moving to an 75

- open position a closed but unlatched door structure hinged on a supporting structure and for checking the opening movement of said door structure when it reaches a predetermined position, said device comprising an arm pivotally secured to one of said structures and extending into the other structure, abutment means associated with and located within the structure into which said arm extends and beyond which abutment means a part of said arm projects, a second abutment means opposed to the first named abutment means, expansible means confined between said two abutment means, the confinement of said expansible means between said two abutment means effecting the desired loading of said expansible means during the closing of the door structure and said expansible means when so loaded being effective to automatically move said door structure, if closed and unlatched, to an open position, and bumper means on the projecting part of said arm for checking contact with abutment means of the structure into which said arm extends when the door structure reaches a predetermined open position, with the consequent checking of further opening movement of said door structure.
4. A device for automatically moving to an open position a closed but unlatched door structure hinged on a supporting structure and for checking the opening movement of said door structure when it reaches a predetermined position, said device comprising an arm pivotally secured to one of said structures and extending into the other structure, abutment means associated with and located within the structure into which said arm extends and beyond which abutment means a part of said arm projects, said abutment means constituting a guide for said arm, a second abutment means opposed to the first named abutment means, expansible means confined between said two abutment means, the confinement of said expansible means between said two abutment means effecting the desired loading of said expansible means during the closing of the door structure and said expansible means when so loaded being effective to automatically move said door structure, if closed and unlatched, to an open position, and bumper means on the projecting part of said arm for checking contact with the aforesaid guiding abutment means when said door structure reaches a predetermined open position, with the consequent checking of further opening movement of said door structure.
5. A device for automatically moving to an open position a closed but unlatched door structure hinged on a supporting structure and for checking the opening movement of said door structure when it reaches its fully open position, said device comprising an arm pivotally secured to one of said structures and extending into the other structure, abutment means carried by and located within the structure into which said arm extends and beyond which abutment means a part of said arm projects, abutment means carried by said arm between said first mentioned abutment means and the pivotal axis of said arm, compression spring means confined between said two abutment means, the confinement of said compression spring means between said two abutment means effecting the desired loading of said spring means during the closing of the door structure and said spring means when so loaded being effective to automatically move said door structure, if closed and unlatched, to an open position, and bumper means on the projecting part of said arm for cooperation with abutment means of the structure into which said arm extends in checking the opening movement of the door structure when it reaches its fully open position.
6. A device for automatically moving to an open position a closed but unlatched door structure hinged on a supporting structure, said device comprising a bracket secured to one of said structures in the region of its hinge edge wall and extending, at least when the door structure is closed, into the other structure, an arm pivotally secured to said bracket and extending at all times into said last mentioned structure, abutment means associated with and located within said last mentioned structure, a second abutment means opposed to the first named abutment means, and expansible means surrounding said arm and confined between said two abutment means, the confinement of said expansible means between said two abutment means effecting the desired loading of said expansible means during the closing of the door structure and said expansible means when so loaded being effective to automatically move said door structure, if closed and unlatched, to an open position.
7. A device for automatically moving to its fully open position a closed but unlatched door structure hinged on a supporting structure and for checking the opening movement of said door structure when it reaches such position, said device comprising an arm pivotally secured to one of said structures and extending into the other structure, abutment means associated with and located within said last mentioned structure and beyond which abutment means a part of said arm projects, a second abutment means opposed to the first named abutment means, compression spring means surrounding said arm and confined between said two abutment means, the confinement of said spring means between said abutment means effecting the desired loading of said spring means during the closing of the door structure and said spring means when so loaded being effective to automatically move said door structure, if closed and unlatched, to its fully open position, and bumper means on the projecting part of said arm for checking contact, when the door structure reaches its fully open position, with abutment means of the structure into which said arm extends, with the consequent checking of further opening movement of said door structure.
8. A device for automatically moving to an open position a closed but unlatched door structure hinged on a supporting structure and for checking the opening movement of said door structure when it reaches a predetermined position, said device comprising an arm connected to one of said structures and extending into the other structure, means carried by said arm and cooperable with abutment means carried by and located within the structure into which said arm extends for automatically effecting opening movement of the door structure upon the unlatching thereof, and means carried by said arm and cooperable with the aforesaid abutment means for checking or arresting the opening movement of said door structure when it has been opened the desired extent.
9. A device for automatically moving to an open position a closed but unlatched door structure hinged on a supporting structure, said device comprising an arm connected to one of said structures and extending into the other struc-

- ture, and means carried by said arm and cooperable with means carried by and located within the structure into which said arm extends for automatically effecting opening movement of the door structure upon the unlatching thereof. 5
10. A device for automatically moving to an open position a closed but unlatched door structure hinged on a supporting structure and for checking the opening movement of said door structure when it reaches a predetermined position, said device comprising an arm connected to one of said structures and extending into the other structure, compression spring means carried by said arm and cooperable with abutment 10 means of the structure into which said arm extends for automatically effecting opening movement of the door structure upon the unlatching thereof, and bumper means carried by said arm within the structure into which said arm extends 20 and cooperable with the aforesaid abutment means of such structure for checking or arresting the opening movement of said door structure when it has been opened the desired extent. 25
11. A device for automatically moving to a predetermined open position a closed but unlatched door structure hinged on a supporting structure, said device comprising an arm connected to one of said structures and extending into the other structure, and compression spring 30 means carried by said arm and cooperable with the structure into which said arm extends for automatically effecting the movement of the door structure to a predetermined open position upon the unlatching thereof. 35
12. A device for automatically opening a closed but unlatched door structure hinged on a supporting structure, said device comprising an arm pivotally connected to one of said structures and extending into the other structure, and spring 40 compression means guided by said arm and located within said last-mentioned structure and cooperable with both of said structures for automatically effecting opening movement of the door structure upon the unlatching thereof. 45
13. A device for automatically moving to an open position a closed but unlatched door structure hinged on a supporting structure and for checking the opening movement of said door structure when it reaches a predetermined position, said device comprising an arm connected to one of said structures and extending into the other structure, abutment means carried by said arm, means cooperable with said arm abutment 5 means and with means carried by and located within the structure into which said arm extends for automatically effecting opening movement of the door structure upon the unlatching thereof, and means carried by said arm and cooperable with the structure into which said arm extends for checking or arresting the opening movement of the door structure when it has been opened the desired extent. 10
14. A device for automatically moving to an open position a closed but unlatched door structure hinged on a supporting structure, said device comprising an arm secured to one of said structures and extending into the other structure, abutment means carried by and located within the structure into which said arm extends, abutment means carried by said arm, and expansible means cooperable with said two abutment means, the cooperation of said expansible means with said two abutment means effecting the desired loading of said expansible means during the closing of said door structure and said expansible means when so loaded being effective to automatically move said door structure, if closed and unlatched, to an open position. 15
15. A device for automatically moving to an open position a closed but unlatched door structure hinged on a supporting structure, said device comprising an arm secured to one of said structures and extending into the other structure, abutment means carried by and located within the structure into which said arm extends and constituting a guide for said arm, abutment means carried by said arm, and expansible means cooperable with said two abutment means, the cooperation of said expansible means with said two abutment means effecting the desired loading of said expansible means during the closing of the door structure and said expansible means when so loaded being effective to automatically move said door structure, if closed and unlatched, to an open position. 20

October 29, 1940.

EDWIN L. ALLEN.

It is hereby certified that error appears in the printed specification of the above numbered patent requiring correction as follows: Page 6, first column, line 39, claim 12, strike out the word "spring" and insert the same after "compression" in line 40, same claim; and that the said Letters Patent should be read with this correction therein that the same may conform to the record of the case in the Patent Office.

Signed and sealed this 14th day of January, A. D. 1941.

(Seal)

Henry Van Arsdale,
Acting Commissioner of Patents.
